2 SHEETS—SHEET 2.

BENJAMIN BROIDO, Inventor

By HIS Attorney *O.V. Kiehl*

UNITED STATES PATENT OFFICE.

BENJAMIN BRODIO, OF NEW YORK, N. Y., ASSIGNOR TO LOCOMOTIVE SUPERHEATER COMPANY, OF NEW YORK, N. Y., A CORPORATION OF DELAWARE.

WATER-TUBE-BOILER SUPERHEATER.

1,328,365.

Specification of Letters Patent. Patented Jan. 20, 1920.

Application filed June 20, 1919. Serial No. 305,520.

To all whom it may concern:

Be it known that I, BENJAMIN BRODIO, a citizen of Russia, and resident of New York, in the county of New York and State of New York, have invented certain new and useful Improvements in Water-Tube-Boiler Superheaters, of which the following is a specification.

My invention relates to boilers of the water tube type in which the water tubes are arranged in spaced rows; and has for its purpose the provision of an improved superheater, the tubular elements of which are located in the spaces between the water tubes.

I deem it expedient to describe my invention by showing it as applied to two different forms of water tube boilers. The principle involved will be appreciated from the description of these two forms and can readily be applied to other boilers, having water tubes similarly spaced. In the drawings which accompany this specification and form a part thereof, Figure 1 is a transverse section taken on line 1—1 of Fig. 2, and Fig. 2 is a longitudinal section taken on line 2—2 of Fig. 1, illustrating one form of boiler with my invention applied. Fig. 3 is a transverse section on line 3—3 of Fig. 4; Fig. 4 is a central longitudinal section of Fig. 3. These two figures show a boiler of another form with my invention in place. Figs. 5 and 6 are views on an enlarged scale which will be found useful in understanding the principle involved in my invention.

In the form of the boiler shown in Figs. 1 and 2, the boiler, which comprises two steam and water drums, 1 and 2, the front water leg 3, the rear water leg 4, and the water tubes 5 joining them, is inclosed in the setting 6. The water tubes 5, it will be noticed, particularly from Fig. 1, are alined and regularly spaced, the arrangement being such that the tubes lie in horizontal rows but are staggered in the other direction so that there are no free vertical spaces between tubes, but spaces at an angle to the vertical. Under the forward end of the tubes 5, there is located the furnace 7 to which access for firing and for other purposes is gained through opening 8, and which is limited at its rear by the bridgewall 9. Baffles 10 and 11 serve to direct the products of combustion from the furnace over the water tubes to the stack connection 12. Steam is taken off from the drums 1 and 2 by means of the

connections 13 and 14 which deliver it to the common steam pipe 15.

The boiler thus briefly described is of a usual construction and is not modified in any particular for the present purposes. Its function may briefly be stated, as follows:

The boiler having been filled to the proper level with water, a fire is built in the furnace, the hot gases from which rise, pass over the first portion of the water tubes 5, then go downward through the space between the two baffles 10 and 11 and finally up through the space between baffle and the rear portion of the setting and so to the outlet 12. In their passage over the tubes, the gases heat the water within the tubes and generate steam which rises principally through the front water leg and is collected in the drums 1 and 2 whence it is taken off by steam pipes 13 and 14.

It has been suggested heretofore to locate the elements of a tubular superheater in the space between the water tubes. I am not aware, however, of any arrangement which presents the advantages of the present one. It will be obvious that the path for the steam through the superheater must be of such size that no appreciable obstruction is presented to the steam flow through the superheater. The usual form of superheaters of this class comprises a header or headers to which the ends of tubular elements are attached, the steam being delivered to one of the headers, leaving it by means of and flowing through the elements during which passage it is superheated, and returning to the other header. If these elements are made large enough to present the requisite space or section for steam flow and are located in the spaces between the water tubes, there will be danger that their presence will seriously obstruct the flow of the hot gases over the water tubes. If, on the other hand, they are made small enough so that they do not interfere with this gas flow, it is impossible by any construction heretofore known to supply enough of them to present an adequate path for the steam flow. In the arrangement according to my invention, the two superheater headers 16 and 17 are placed transversely under the forward water leg. The upper one of them, 16, has connected to it the pipe 15, while from the end of the lower one, 17, steam is taken off at the point 18. Connected to the

upper header 16, there is a series of secondary headers or sub-headers, 19. These, as will be seen, are curved and extend into the diagonal spaces between the water tubes 5 adjacent to the front water leg 3. They are of a diameter substantially equal to the distance between the water tubes so that they practically fill this space. While they are shown as being cylindrical, it is evident they 10 may be of some other shape. A similar series of sub-headers, 20, is connected with the lower header, 17, and extends into the same spaces adjacent to the sub-headers, 19, and parallel to them but on the side away from 15 the water leg 3. The members of this second series, 20, are shorter than those of the first series, 19. They may also be of some other than circular cross-section. The particular means used to secure these sub-headers to the main headers 16 and 17 forms 20 no part of my present invention and may be of any description desired. I prefer, however, that they be of such a nature that they permit ready detachment and re-attachment. Secured to the sub-headers 19 and 25 20 are the U-shaped superheater elements 21. One end of each of them is connected to a sub-header 19 of a pair of sub-headers which lie within the same space, the other 30 end being connected to the sub-header 20 of the same pair, and the straight, parallel lengths of the element extending parallel to the water tubes. As appears clearly in Fig. 2, a series of such U-shaped elements 35 21 connects each pair of sub-headers, the elements being of graded sizes and arranged one within the other. The elements 21 are preferably fixed to the sub-headers 19 and 20 in a permanent manner, such as results 40 by welding them to these sub-headers, and two sub-headers together with their elements 21 constitute what may be termed a single unit. To remove such a unit, the connection with headers 16 and 17 is broken, 45 after which the unit can be lowered into the furnace space 7 from which it can be removed through the door 8.

Referring now for a moment to Figs. 5 and 6, there will be found here a more or 50 less diagrammatic representation of some of the parts just spoken of, which will serve to make clearer one important feature of my invention. In these two figures, the sub-headers 19 and 20 are seen to be of the size 55 mentioned, *i. e.* of such size as to extend from one row of water tubes to the next one; while the elements 21 are considerably smaller in diameter. This principle constitutes the basis of my invention. Its advantage is that it permits a large total path for 60 steam flow through the superheater and yet presents a comparatively small obstruction to the flow of the gases between the water tubes. At the same time the sub-headers 65 and the connections of the elements to them

are out of the direct line of the hot gases, and so less liable to injury from this source.

The function of my device will be apparent from what has been said. Steam, delivered to the header 16 by the pipe 15, is 70 conveyed by this header to the sub-headers 19 which in turn deliver it to the elements 21. While flowing through these elements, it is subjected to the heating effect of the gases from the furnace and is delivered to 75 the sub-headers 20 in a superheated state. These sub-headers deliver it to the lower header 17 from the end 18 of which it is taken off and carried to the point of use.

In the form of water tube boiler illustrated in Figs. 3 and 4, the constituent parts of the boiler may be briefly given, as follows: Water tubes 5 arranged in regularly spaced rows connect the upper drum 22 with the lower drum 23. This structure is 80 enclosed in a housing 6 from the forward side of which extends the furnace space 7. A baffle 24 serves to direct the gases coming from the furnace 7 so that they are constrained to flow first upward over a portion 85 of the water tubes 5 and then downward through the remaining portion to the stack connection 12.

The sub-headers 19 and 20 of the superheater are in this case shown as extending 90 into the space between tubes 5 near the top of these tubes and adjacent to the drum 22. The sub-headers 19 are again longer than those of the set 20 and the U-shaped elements 21 are permanently connected to sub-headers 19 and 20 in a manner similar to that previously described.

The principle emphasized above, by which the elements 21 are small enough not to obstruct the flow of gases while the sub-headers 105 19 and 20 are as large as the spacing admits, is again adhered to. Headers 16 and 17 are in this case given a shape, as will be gathered from Fig. 3, bringing it into close proximity to the side of the housing 6. 110 Steam is delivered to the header 16 in this case by the steam pipe 15, leading from the upper portion of the drum 22.

The function of the boiler and my apparatus will be perfectly evident and requires 115 no further statement. To remove a unit made up of a pair of sub-headers 19 and 20, and the attached elements, its connection with headers 16 and 17 is broken, after which the element can be moved downward 120 into the space in which it is located and removed through the furnace space 7.

Wherever in this specification or in the claims the term "headers" is used, it is meant to include not only such structures as 3 and 125 4 in Fig. 2 but also such drums as 22 and 23 in Fig. 4.

In practice, many variations in the details of my invention will occur. Thus the straight parallel lengths of the U-shaped ele- 130

ments need not necessarily be parallel to the water tubes; or instead of a mere U-shaped unit a serpentine form may be employed. As long as these variations do not lose the spirit 5 and underlying principle of my invention, they are to be considered as included in the subjoined claims.

What I claim is:

1. In a boiler, the combination of two parallel water legs; water tubes connecting them and arranged in spaced rows; a pair of parallel superheater headers adjacent to one of the water legs and arranged transversely to the water tubes; a sub-header secured to one 10 of the headers and extending into the space between two rows of water tubes and adjacent to the water leg; a second sub-header secured to the other header and extending into the space on the side of the first away 15 from the water leg and not as far as the first; both sub-headers being of a diameter substantially equal to the space between the rows of tubes; and a plurality of tubular superheater elements attached to the pair 20 of sub-headers and extending into the space between the water tubes, the elements being of materially smaller diameter than the space.
2. In a boiler, the combination of a front 25 and a rear water leg; water tubes connecting them and arranged in spaced rows; means to direct a flow of hot gases across the water tubes; a pair of superheater headers adjacent and transverse to the water 30 tubes; a pair of parallel, adjacent sub-headers attached one to each header and extending for unequal distances into the space be-

tween two rows of water tubes and out of the direct path of the gases, each sub-header being of a diameter substantially equal to 40 the space between the rows; and superheater elements, materially smaller in diameter than the sub-headers, located in the space between the water tubes and out of contact 45 with them and secured to the sub-headers.

3. In a boiler, the combination of a water leg; two parallel spaced rows of water tubes secured to the water leg; a superheater sub-header in the space between the rows and adjacent to the water leg; a second and 50 shorter sub-header in the space parallel and adjacent to the first on the side remote from the water leg; a plurality of looped superheater elements whose ends are secured to the two sub-headers respectively, and which 55 extend into the space between the tubes; and two superheater headers lying outside of and transversely to the space between the rows of water tubes and to which the sub-headers are secured.

4. In a boiler, the combination of a plurality of water tubes arranged in spaced rows and secured to a water leg; a superheater unit located in the space between two rows comprising a pair of sub-headers extending substantially from one row to the other, and a plurality of elements connected to the sub-headers and extending into the space away from the water leg and spaced from both rows.

Signed at New York in the county of New York and State of New York this 19th day of June A. D. 1919.

BENJAMIN BROIDO.
